COMBINED BOTTLE AND DISPENSING CAP

Albert H. Torongo, Washington Crossing, N.J., assignor
to Johnson & Johnson, a corporation of New Jersey

Filed Jan. 3, 1964, Ser. No. 78,058

Term of patent 14 years

(Cl. D58—6)

FIG. 1 is a side elevational view of a combined bottle and dispensing cap, showing my new design;

FIG. 2 is a front elevational view thereof;

FIG. 3 is a side elevational view thereof taken from the right of FIG. 2;

FIG. 4 is a top plan view thereof; and

FIG. 5 is a bottom plan view thereof.

The rear, not shown, of my combined bottle and dispensing cap design is a mirror image of the front shown in FIG. 2.

I claim:

The ornamental design for a combined bottle and dispensing cap, as shown and described.
